B. H. HOWARD ET AL

INGOT MOLD

Filed Nov. 1, 1924.

UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

INGOT MOLD.

Application filed November 1, 1924. Serial No. 747,332.

To all whom it may concern:

Be it known that we, BLOOMFIELD H. HOWARD AND ERNEST J. TURNER, citizens of the United States, residing, respectively, at 5 Washington, District of Columbia, and Pittsburgh, in the county of Allegheny and State of Pennsylvania, have invented certain new and useful Improvements in Ingot Molds, of which the following is a specification.

Our invention relates to improvements in ingot molds.

The object of our invention is to provide an ingot mold for casting steel ingots having its upper end constructed to receive a feeder, whereby the ingot cast in the mold will be free of holes and seams known as "piping" and also reduce segregation.

Another object of our invention is to 20 provide a mold of this character in which the feeder is more rigidly held within the bore of the mold and adapted to receive feeders in which there is a slight variation in the diameter thereof.

25 A further object of our invention is to provide a simple, cheap and effective mold of this character hereinafter more fully described.

In the accompanying drawings:

30 Figure 1 is a perspective view of our improved mold showing a feeder applied thereto.

Figure 2 is a vertical transverse sectional view of Figure 1.

35 Figure 3 is a vertical transverse sectional view of a mold showing a modified form.

Figure 4 is a top plan view of another modified form.

40 Figure 5 is a vertical transverse sectional view of a further modified form of mold.

Figure 6 is a vertical transverse sectional view of a still further modified form of mold.

45 Figure 7 is a vertical transverse sectional view of one side of the mold showing a slightly modified form from that shown in Figure 5.

Figure 8 is a vertical sectional view of 50 one side of the mold showing a slightly modified form of the form shown in Figure

Referring now to the drawings, 1 represents the mold which is of the usual construction, having the side walls slightly increasing in thickness towards the lower end; the upper end of the mold, around the bore, is provided with a flared portion 2 adapted to correspond with the flared outer portion 3 of the feeder 4. From the construction it will be seen that the feeder 4 is tightly wedged within the upper end of the mold.

In the modification shown in Figure 3, the flare at the upper end of the mold 1 has the two portions 5 and 6 extending at different angles. In this form a feeder having a corresponding outer wall would be employed.

In the modification shown in Figure 4, the upper edge of the mold is provided with 70 the beveled recesses 7, 8, 9 and 10 and the four walls adapted to receive wedges whereby a tubular feeder having perfectly plain outer walls can be used on the mold.

In the modification shown in Figure 5, 75 the upper edge of the mold is convex as indicated at 11, and the feeder would have its outer face correspondingly shaped.

In Figure 6, the upper edge of the mold is concave as indicated at 12 and in this 80 form the feeder would have a correspondingly shaped outer face.

In Figure 7, the convex wall 13 extends from the bore of the mold to the outer face 14.

85 In Figure 8, the convex cut away portion 15 extends from the bore of the mold to the outer wall 16.

Having thus fully described our invention what we claim is:

1. An ingot mold having a bore therethrough flared outwardly.

2. An ingot mold having a flared bore adapted to receive a feeder.

3. An ingot mold comprising a body portion having a bore therethrough, and having its upper end flared outwardly.

4. An ingot mold comprising a body portion having a bore therethrough, and having a curved outwardly flared upper end communicating with the bore of the mold.

5. An ingot mold comprising a body por-

tion having a bore therethrough, and having a flared upper end, and a feeder extending into the bore of the mold and having its outer wall resting upon the flared upper end of the mold.

6. An ingot mold comprising a body portion having a bore therethrough, and hav-

ing a flared upper end, and a feeder extending into the mold and having its outer wall correspondingly shaped.

In testimony whereof we affix our signatures.

BLOOMFIELD H. HOWARD.

ERNEST J. TURNER.
